HAIR CURLER

Bernard A. Sterling, Chicago, Ill.

Application June 28, 1939, Serial No. 281,617

7 Claims. (Cl. 132—33)

This invention relates to hair waving apparatus and, more particularly, to an improved curler for producing Croquignole waves.

Croquignole waving is so well understood in the art that further description of the same is considered unnecessary except to state that, in general, such waving comprises winding the strands of hair spirally from their outer ends upon a curler and then moistening and subjecting the same to heat.

One of the main objects of the invention is to provide a curler which is adapted not only to wind the hair into the desired wave, but is also adapted to tension the hair or produce a tight wind without the necessity of pulling the hair taut as it is wrapped about the curler, and without the necessity of gripping the hair adjacent to the scalp to distribute the pull over the entire section of skin from which the strand extends as contemplated heretofore in the art.

It is also an object of the invention to provide a curler of simple and inexpensive construction, and which may be handled and operated conveniently and effectively; also a curler composed of few parts and having means thereon for tensioning the hair as it is wound.

Further objects and advantages of the invention will appear from the following detailed description, taken in connection with the accompanying drawing in which:

Figure 1 is a fragmentary perspective view of a portion of a person's scalp showing, more or less illustratively, the manner of waving the hair with the curler of the present invention;

Figure 2 is a side view of the curler;

Figure 3 is a transverse section taken on the line 3—3 of Figure 2;

Figure 4 is a fragmentary longitudinal section taken on the line 4—4 of Figure 3;

Figure 5 is a side view of the curler taken at right angles to Figure 2;

Figure 6 is a plan view of another form of protector for use with the curler;

Figure 7 is a transverse section taken on the line 7—7 of Figure 6; and

Figure 8 is a transverse section taken on the line 8—8 of Figure 6.

In carrying out the present invention, the first step is to divide the hair 5 into a lock or strand 6. A suitable protector 7 is placed upon or over the strand 6 adjacent the scalp (Figure 1) to protect the scalp against the heat of the waving operation.

The protector 7 comprises a heat insulating pad of felt or other suitable material having a

slit 8 through which the strand of hair 6 is passed as shown in Figure 1. The protector 7 is illustrative of one suitable protector for protecting the scalp against the heat of the waving operation without gripping the hair adjacent to the scalp to distribute the pull over the section of skin from which the strand 6 extends, so that the hair may be pulled taut from the scalp to produce a tight wave as contemplated heretofore in the art.

The curler indicated in its entirety at 10 comprises a metal spool or reel 11 of circular section diminishing in diameter from its opposite ends to approximately the center thereof. A retainer tongue 12 is pivoted at 13 in a groove 14 at one end of the spool 11. A spring 15 tends to hold the retainer 12 yieldingly against the spool 11, and the retainer 12 has a finger piece 16, depression of which swings the retainer 12 away from the spool 11 to permit the outer end of the strand of hair 6 to be placed therebetween and, if desired, to facilitate removal of the waved hair therefrom.

A collar 18 fits telescopically over the spool 11 at 19 and is held in place, for instance, by a second collar 20 which fits telescopically upon the spool 11 at 21. The spool 11 may be peened over or center-punched at 22 to secure the collar 20 in place on the spool, or the collar 20 may be secured in place by pressed fit on the spool or otherwise as desired. The spool 11 is provided with a finger piece at 23 for turning the spool in the collar 18.

Pivoted at 25 between lugs 26 on the collar 18 is a tensioning tongue 27. This tongue 27 is formed of a thin spring metal strip generally following the longitudinal contour of the spool 11 and turned in at its free end and provided with an opening 28 which is adapted to be snapped into and out of engagement with a pin 29 formed, for instance, integral with the spool 11 and extending axially from the adjacent end thereof. The inturned end 30 of the tensioning tongue 27 is turned out at 32 to form a finger piece for engaging the tongue 27 with and disengaging same from the pin 29.

After dividing the hair into the strand 6 and positioning the protector 7 in place as described, the free or outer end of the strand of hair is clamped between the retainer tongue 12 and the spool 11 preferably approximately intermediate the ends of the spool. This may be accomplished by depressing the finger piece 16 to swing the tongue 12 from the spool, then placing the outer

end of the strand of hair in place and releasing the finger piece, whereupon the tongue grips the hair yieldingly under the action of the spring 15.

Now, by holding the collar 18 or the tensioning tongue 27 with one hand and grasping the finger piece 23 with the other hand, the spool is turned in the collar 18 and with respect to the tongue 27 to wind the strand of hair 6 spirally from its outer end onto the spool 11 up to or nearly to the protector 7. As the spool 11 is turned, the hair is wound not only around the spool but between the spool and the tensioning tongue 27. The tongue 27, due to its resilient or inherently spring character, imposes a constant and increasing tension upon the wound hair as it is wrapped upon the spool. As a result, the hair is tensioned to produce a tight wind, and this is accomplished without pulling the hair taut from the scalp or from a clamp as it is wrapped about the curler.

Instead of requiring the hair to be pulled taut, the hair may be left slack as indicated, for instance, in Figure 1, and yet the desired tight wind is secured. This makes it unnecessary to grip the strand of hair 6 adjacent the scalp with a clamp with a view to distributing the pull over the entire section of the skin from which the strand extends.

A corrugated spring disc washer 35 is positioned upon the spool 11 between the shoulder 36 (Figure 4) and the collar 18 and restrains or stops relative, and particularly relative retrograde, rotation between the collar 18 and tensioning tongue 27 and the spool 11 under the action of the wound hair, for instance, when the finger piece 23 is released.

After the strand of hair is wound as described, a pad is then applied and, with it, the desired waving solution, whereupon a heater may be applied to produce the permanent wave desired. Instead of using a heater, the pad may contain, for example, copper chloride, talc and aluminum, or other suitable chemical means which will develop heat upon moistening with water. These features per se form no part of the present invention and are so well understood by those skilled in the art that further description of the same is considered unnecessary.

Upon completion of the wave the tensioning tongue 27 is opened and the wound or waved strand of hair may be slipped longitudinally from the curler.

The form of protector designated in its entirety at 40 in Figure 6 may be used instead of the protector 7. It comprises a pair of metal jaws 41, 42, one of which is fixed between plates 43. The other jaw 42 is pivoted at 60 between the plates 43 and is thereby pivoted to the jaw 41. The jaws 41, 42 are covered wholly or partially as shown by sheaths 44 of rubber or other suitable material and have finger pieces at 45 for swinging the jaws to open position. The outer end of the jaw 41 is notched at 46, and a spring detent 47 is anchored to the other jaw 42 at 48. The detent 47 has a catch 49 which is adapted to snap into the notch 46 to hold the jaws 41, 42 closed and the extending end 50 provides a finger piece for releasing the detent in order to open the jaws.

A lug 52 formed integral with or secured to the jaw 42 forms a stop for limiting the releasing movement of the detent 47 and for retaining same in the desired position. Pads 54 of felt or

other suitable material are glued or otherwise secured to the inner sides of the sheaths 44 and cover the jaws to assure adequate insulation between the head and the heater. The jaws are preferably curved to conform substantially to the curvature of the head.

In the use of the protector 40 the jaws are opened and placed over the strand of hair 6 adjacent to the scalp, whereupon the jaws are released and swing to closed position under the action of a spring indicated at 56. Upon reaching closed position the detent 47 snaps into place to lock the jaws closed upon the strand of hair. This form of protector is not intended to grip the hair in a manner to distribute any pull over the entire section of skin from which the strand extends because, as before, pulling of the hair from the scalp or from a clamp placed upon the strand of hair adjacent the scalp is not relied on to provide the desired tight wind. The tight wind and the desired tensioning of the hair as it is wound is secured by the tensioning tongue 27 of the curler as before.

I claim:

25 1. A hair waving curler comprising a spool, a retainer for gripping a strand of hair to said spool, a tensioning tongue carried by said spool for tensioning the hair as it is wound on the spool, said spool being adapted to be turned relative to said tongue, and a pin projecting endwise from said spool, said tongue being turned in and adapted for releasable engagement with said pin.

35 2. A hair waving curler comprising a spool, a retainer for gripping a strand of hair to said spool, a tensioning tongue pivotally supported at one end on said spool, said tongue being of resilient character to tension the strand of hair as it is wound on said spool, said spool being adapted 40 to be turned relative to said tensioning tongue, and a pin projecting endwise from said spool, said tensioning tongue being turned in and adapted for releasable engagement with said pin.

45 3. A hair waving curler comprising a spool, a retainer pivoted to said spool, a spring interposed between said retainer and said spool for holding the retainer yieldingly in position to grip a strand of hair, a tensioning tongue pivotally supported at one end on said spool, said tongue being of 50 resilient character to tension the strand of hair as it is wound on said spool, said spool being adapted to be turned relative to said tensioning tongue, and a pin projecting endwise from said spool, said tongue being turned in and adapted for releasable engagement with said pin.

55 4. A hair waving curler comprising a spool, a collar mounted on said spool, a tensioning tongue pivoted to said collar at one end and adapted to tension the hair as it is wound on the spool, and a pin projecting endwise from said spool, said tensioning tongue being turned in and adapted 60 for releasable engagement with said pin.

65 5. A hair waving curler comprising a spool, a tensioning tongue pivotally carried in proximity to one end thereof by said spool and adapted for tensioning the hair as it is wound on the spool, and means cooperating with said tongue in proximity to the opposite end thereof for holding the tongue to the spool, said tongue being adapted to be released from said holding means to free the tongue for swinging movement to open position.

70 6. A hair waving curler comprising a collar, a spool mounted to turn in said collar, a retainer for gripping a strand of hair to said spool, a tensioning tongue pivoted in proximity to one

end thereof on said collar and adapted for tensioning the hair as it is wound on the spool, and means cooperating with said tongue in proximity to the opposite end thereof for holding the tongue to the spool, said tongue being adapted to be released from said holding means to free the tongue for swinging movement to open position.

7. A hair waving curler comprising a collar, a spool mounted to turn in said collar, a retainer

5 for gripping a strand of hair to said spool, a tensioning tongue pivoted in proximity to one end thereof on said collar and adapted for tensioning the hair as it is wound on the spool, and means disposed between said spool and said collar for restraining the spool against free retrograde turning movement relative to said collar.
